PORTABLE ELECTRIC TOOL

Frithiof P. Forss, Aurora, Ill., assignor to Independent Pneumatic Tool Co., Chicago, Ill., a corporation of Delaware

Original application July 23, 1934, Serial No. 736,502. Divided and this application March 23, 1936, Serial No. 70,241

4 Claims. (Cl. 51—170)

This application is a division of my co-pending application, Serial No. 736,502, filed July 23, 1934.

In portable electrically actuated rotary tools, the driving shaft or spindle of the tool is rotated by an electric motor carried within the casing of the tool. The commutator and the armature of the motor are connected by the required number of lead wires arranged in an annular group between them. These wires, by reason of the close spacing between the commutator and the armature, are relatively short, extending directly from the commutator segments to the windings of the armature. These wires rotate as a group with the armature and the commutator and in tools as heretofore constructed are injured by the vibrations transmitted to the armature from the driving shaft or spindle of the tool. These vibrations are especially severe in rotary grinders, wherein a grinding wheel is directly connected to and rotated by the spindle of the tool. This vibration crystallizes the lead wires, causing them to break off and short circuit the motor of the tool. This vibration also subjects the gearing and the bearings in the tool to undue wear.

The general purpose and object of my invention is to provide means in the tool between the grinding wheel and the motor to eliminate or deaden these vibrations and thus prevent crystallization and breaking of the lead wires and also undue wear on the gearing and the bearings.

In carrying out the object of my invention, I provide the driving shaft or spindle of the tool with a flexible section so constructed and arranged that vibrations generated by the grinding wheel when in operation will not injure the lead wires or produce undue wear on the gearing or the bearings of the tool.

The invention consists further in the features hereinafter described and claimed.

40 In the accompanying drawing:—

Fig. 1 is a longitudinal sectional view with parts in elevation of a portable electrically operated grinder embodying the flexible shaft section of my invention;

45 Fig. 2 is a larger view of the flexible shaft section and the portion of the tool containing the same to more clearly illustrate the construction; and

Fig. 3 is a transverse sectional view taken on line 3—3 of Fig. 2.

50 In the drawing, 1 indicates the electric motor of the tool having a stator 2 and an armature 3. The armature is disposed within the stator and is keyed or otherwise fixedly secured to the armature shaft 4. The latter extends beyond the op-

posite ends of the armature and is journaled at its ends in anti-friction bearings 5, 6 supported in the outer casing of the tool. The forward end of the shaft 4 is provided with gear teeth 7 which mesh with a speed reducing gear pinion 8 fixed to the inner end portion 9 of the spindle or driving shaft of the tool, to be presently described. The opposite end of the shaft 4 supports a commutator 10 engaged by the usual brushes, one of which is shown at 11. The brushes are connected with the current supply wires for the tool through a switch device 12 in the handle section 13 of the tool. The switch device has a manually operable actuating member 14 accessible from the exterior of the handle section and slidably mounted therein as shown. The supply wires extend into the handle section through a carrying tube 15 as shown.

The commutator 10 is located closely adjacent the armature 3 and the segments of the commutator are connected with the windings of the armature by a plurality of lead wires 16, 16 arranged in an annular group between the commutator and the armature. By reason of the close spacing of these parts, the lead wires 16 are relatively short and extend directly from the commutator to the armature.

The spindle of the tool, in accordance with my invention, contains a flexible section comprising the inner portion 9 heretofore referred to, a forward portion 17 and an intermediate portion consisting of a pile of thin flexible steel blades 18, 18. The blades extend between and connect the spindle portions 9 and 17 for the rotation of one by the other. To accomplish this, the blades extend into transverse slots 19, 19 in the spindle sections as shown. The blades are arranged to have flat-wise contact with each other and thus mutually support one another to provide a solid driving connection for the spindle sections. The blades are enclosed in a sleeve 20 which extends between the spindle sections and fits about the same as shown. Thus, the sleeve prevents displacement of the blades from the slots, the sleeve extending over the slots at the sides of the spindle sections as illustrated in Fig. 3. It will be observed that the blades fill the slots and have their side edges in contact with the inner surface of the sleeve.

The sleeve 20 has a pressed fit on the spindle section 17 and a rotative fit on the section 9. Thus the section 17 may turn relatively to the section 9 in response to a torque strain imparted to the section 17 by the grinding wheel 21 secured to its outer end. This torque strain twists or flexes the blades 18 in a radial or spiral

direction, as indicated by the dotted lines in Fig. 3, and the vibrations thus imparted to the spindle by the grinding wheel are absorbed or deadened in the spindle and are not transmitted to the armature shaft of the motor to crystallize and break the lead wires 16, as heretofore. Moreover, the bearings and the gearing of the tool are also relieved of these strains and undue wear on these parts is to a large extent eliminated. These strains are especially severe in portable rotary grinders. A tool of this character is rotated at a relatively high speed, and the grinding wheel at top speed is pressed against the work in the use of the tool. On contact with the work, the speed of the wheel is suddenly reduced by the frictional resistance offered to its rotation and the shock so imparted to the spindle is taken up by the blades 18 which flex or twist in response to this applied strain. These shocks are repeatedly applied to the spindle as the grinding wheel is moved over the work, the rotation of the wheel being retarded as it contacts with the work and accelerating as it is lifted from or freed the work. With the spindle sections 8 and 17 relatively rotatable, the blades may twist or flex in response to these torque strains, and the tool parts and the lead wires to the rear of the blades will be relieved of these shocks and jars. Thus, the lead wires in particular will be protected from breakage and short circuiting of the motor will be prevented.

The blades 18 have a loose or sliding fit in the slots 19 and the latter have their outer ends beveled outwardly as at 22 to facilitate twisting of the blades. The ends of the blades abut against the ends of the slots. The bearings 23, 24 journal the spindle in the tool casing 25 which is provided for the spindle and this casing is secured to the motor case 26 at its end opposite the handle section 13. The bearing 24 which journals the spindle section 17 in the casing 25 is clamped solid in the casing by a ring nut 27. The spindle section 8 is journaled in the casing 25 by the bearing 23, and the inner end of this section is opposite an abutment 28 carried by a fixed part of the tool casing, as for example the plate 29 which is clamped between the casings 25 and 26 to divide one from the other and which plate also provides a support for the bearing 5 for the armature shaft 4. Abutment 28 is provided to limit the endwise move-

ment of the spindle section 8 toward the motor 4. The ring nut 27 is screwed into the opposite end of the casing 25, the latter being internally screw threaded to receive the nut. The bearings are of the anti-friction type as shown. The blades will twist in response to those torque strains which enable or cause one spindle section to rotate relatively to the other and thus relieve one section of shock or jar imparted to the other.

The details of construction and arrangement of parts shown and described may be variously changed and modified without departing from the spirit and scope of my invention except as pointed out in the appended claims.

I claim as my invention:

1. In a portable tool, an electric motor, a spindle driven by said motor, a tool member mounted for direct drive on the spindle, and torque responsive means incorporated in the spindle to relieve the motor of vibrations imparted to the spindle by the tool member in the use of the tool.

2. In a portable tool, an electric motor, a spindle driven by said motor, a tool member mounted for direct drive on the spindle, and torque responsive means consisting of flexible blade means incorporated in the spindle to relieve the motor of vibrations imparted to the spindle by the tool member in the use of the tool.

3. In a portable tool, an electric motor, a spindle driven by said motor, a tool member mounted for direct drive on the spindle, the latter having axially spaced sections, and torque responsive means consisting of flexible blade means extending between and fitting in slots in said sections to relieve the motor of vibrations imparted to the spindle by the tool member in the use of the tool.

4. In a portable tool, an electric motor, a spindle driven by said motor, a tool member mounted for direct drive on the spindle, the latter having axially spaced sections, torque responsive means consisting of flexible blades extending between and fitting in slots in said sections to relieve the motor of vibrations imparted to the spindle by the tool member in the use of the tool, and a sleeve element about the blades and the spindle sections to hold the blades between the sections and in the slots.
